In Germany April 8, 1939

6 Claims. (Cl. 128—171)

The present invention relates to air-cooled aircraft engines the cylinders of which are arranged in line. More particularly the present invention refers to the manner of guiding the cooling air to be led along the cylinders through the space enclosed by the engine cowling.

Hitherto it has been usual to provide at the front side of the engine cowling and in the side wall thereof an admission opening facing the relative air current and discharge openings for the cooling air which is compressed in front of the cylinder row, whereas behind the cylinders an area of reduced air pressure is formed. In this design the pressure gradient between the pressure space, provided below the cowling and in front of the cylinders, and the suction space arranged behind the cylinders is not uniformly distributed over all the cylinders. The total pressure gradient of the air applied to an individual cylinder decreases in the direction of flight from the rear cylinders to the front cylinders. Since the degree of cooling depends on the magnitude of the total pressure gradient of the air the cooling of the front cylinders of an engine having cylinders arranged in line is worse than that of the cylinders situated further rearwardly. The reason for this defective cooling is the non-uniform distribution of the pressure generated in the pressure space. In this case the pressure is lowest at the foremost cylinder and increases towards the adjacent cylinders, while the pressure in the suction space shows a nearly uniform distribution behind all the cylinders of an engine having cylinders arranged in line.

In order to obtain satisfactory cooling current proportions in connection with star-type engines an opening or a channel for withdrawing the cooling air has been provided at the bilge of the engine cowling, i. e., in the range of the change-over zone from the front side of the cowling to the lateral wall thereof, that is at a point where the pressure of the flowing outer air is very low.

According to the invention the low pressure prevailing outside of the bilge of the cowling of an engine with cylinders disposed in line is utilized for improving the pressure and flowing properties of the cooling air.

According to the invention, therefore, one or more nozzles are provided in the bilge for leading the cooling air current to the front cylinders, whereas the cooling air current for the rear cylinders is admitted by nozzles provided in the side wall of the cowling. For obtaining uniformity of the cooling air current for all cylinders the suction space is subdivided and the separate spaces

are connected by air channels, the cross sections of which may be regulated.

In accordance with the invention it is also possible to provide one or more discharge nozzles in the bilge only without subdivision of the suction space to obtain a uniform cylinder pressure gradient, because the cooling air current acting upon the rear cylinders must flow over a longer path on its way through the pressure space and therefore is subjected to greater losses of pressure.

In the accompanying drawings some constructions according to the invention are shown diagrammatically by way of example.

In the drawings:

Figures 1 and 2 show one of the known constructions and the corresponding curve diagrams indicating the pressure distribution.

Figures 3 and 4 show a construction in which in a manner known per se an air discharge opening is provided in the rear wall portion of the engine cowling and a reversing nozzle is arranged in the bilge of the engine cowling, and indicating the pressure distributing diagram resulting from this construction.

Figures 5 and 6 show a control wall between the suction space of the front cylinders and the suction space extending over all the other cylinders of the row together with the pressure distributing diagram corresponding to this particular device.

Figure 7 shows a construction of an engine cowling in which the air discharge is limited to the reversing nozzle arranged in the bilge of the cowling.

Figure 8 shows a curve diagram relating to the construction illustrated in Fig. 7, and

Fig. 9 is a detail view of the controllable openings in the wall shown in Figs. 5 and 7.

In the known constructions the cooling air enters the space below the engine cowling through an opening 1 which, as may be seen from Figure 1, faces the air current that is compressed due to flight. This cooling air is compressed in front of the cylinders mounted in space 2 and escapes through openings 4 and 5 from the cowling after traversing suction space 3 arranged behind the row of cylinders. The pressure distribution existing in the pressure and suction space is shown in Figure 2 in which the curves P_s and P_d illustrate the pressure prevailing in the suction and pressure space respectively, whereas the total pressure loss is designated with Δp .

From the smooth course of the curve P_s it will be seen that the pressure level in the suction space extends nearly uniformly over all the cyl-

inders, whereas behind the line P_D the pressure level in the elevated pressure space decreases from the rear cylinders to the front cylinders; the cylinders arranged in the most forward position being particularly influenced by this pressure drop.

This action detrimental to the cooling effect is obviated according to the present invention by the fact that, as shown in Figure 3, a reversing nozzle 6 is mounted in the bilge of the cowling. This nozzle creates a lower pressure level in the suction space 3 (Figure 3), the pressure gradient having its largest value at the cylinder arranged as far in front as possible. As shown in Figures 5 and 6, discharge opening 5 is provided at the rearward portion of the cowling. Wall 7 which is preferably vertically arranged is inserted in the cowling in the level of the cylinder arranged farthest in front. Wall 7 perfectly closes the suction space of the front cylinder or of the front cylinders with regard to that of the other cylinders. Thus, a pressure level according to line Ps_1 of Figure 6 is obtained the curve of which merges into the line Ps_2 , if partial division of the spaces from each other is effected by separator wall 7 provided with discharge openings 9 the cross sections of which may eventually be altered.

The cross section of openings 9 in separator wall 7 may be made smaller or larger by means of hinged control flaps 10 shown particularly in Fig. 9. Flaps 10 are connected with rods 11 which in turn are connected with rods 12. Rods 12 have pins which slide in slots 13 of plate 14. When plate 14 is moved up from its position shown in Fig. 9, rods 12 are turned outwardly in opposite directions and move flaps 10 into the position shown in dotted lines. Plate 14 may be actuated by any suitable means.

If the curve shown in Figure 6 is compared with the curve of Figure 2, it will be seen that the provision of separator wall 7 results in a sudden reduction of the level of the reduced pressure in suction space 8 adjacent reversing nozzle 6 and coordinated to the foremost cylinders which in turn causes a corresponding increase of the total pressure gradient relating to these cylinders.

The curve shown in Figure 4 is not substantially altered if, as shown in Figure 7, the engine cowling, setting aside the air discharge at the reversing nozzle 6, is closed against the outer air flow and if the hitherto usual air discharge openings are totally omitted. This is due to the fact that a portion of the total pressure gradient S_p of the rear cylinders is consumed by the flow of the cooling air through the suction space (see Figure 8). In Fig. 8, Δp designates the total pressure difference between the elevated pressure space and the suction space, while δp indicates the pressure differences within the suction space.

As the cross sections of the openings or nozzles in the separator wall may be regulated as shown particularly in Fig. 9, the total pressure gradient of the front cylinders of the row may be so increased that the cooling of these cylinders is increased and the cooling of all cylinders of the engine is made uniform as far as possible.

Finally according to the invention the wall portion of reversing nozzle 6 facing the interior of the cowling may be hingedly connected in a manner to be capable of swinging towards the interior so that the cross section of the opening may be adjusted.

What I claim is:

1. In an air cooled internal combustion engine having groups of cylinders arranged in line, a device for the distribution of cooling air to the cylinders comprising a cowling surrounding said cylinders and provided with an inlet opening at the front portion thereof positioned laterally on one side with respect to the longitudinal plane passing through the axes of said cylinders, an air pressure space and an air suction space being formed within said cowling, said air pressure space extending behind said inlet opening parallel to and divided by said cylinders from said air suction space extending substantially symmetrical to said air pressure space, the width of said air suction space increasing from the front end to the rear end thereof, said cowling further comprising an air discharge opening provided in the front portion thereof and arranged on the other side of said longitudinal plane in a region where the outer air pressure is reduced, a wall having openings for controlling the flow of cooling air therethrough and being provided behind the front cylinders of each group of cylinders, and at least one air discharge opening at the rear end of said cowling.

2. In an air cooled internal combustion engine with cylinders arranged in line, a device for the distribution of cooling air to the cylinders comprising a cowling surrounding said cylinders and provided with an inlet opening at the front portion thereof positioned laterally on one side with respect to the longitudinal plane passing through the axes of said cylinders, an air pressure space and an air suction space being formed within said cowling, said air pressure space extending behind said inlet opening parallel to and divided by said cylinders from said air suction space extending substantially symmetrical to said air pressure space, said cowling being shaped to provide for a width of said air suction space increasing from the front end to the rear end thereof, said cowling further comprising an air discharge opening provided in the front portion thereof and arranged on the other side of said longitudinal plane in a region where the outer air pressure is reduced, a wall having openings for controlling the flow of cooling air therethrough and being provided between the front cylinders of each row of cylinders, and air discharge openings provided at the rear end of said cowling.

3. In an air cooled internal combustion engine with cylinders arranged in line, a device for the distribution of cooling air to the cylinders comprising a cowling surrounding said cylinders and provided with an inlet opening at the front portion thereof positioned laterally on one side with respect to the longitudinal plane passing through the axes of said cylinders, an air pressure space and an air suction space being formed within said cowling, said air pressure space extending behind said inlet opening parallel to and divided by said cylinders from said air suction space extending substantially symmetrical to said air pressure space, said cowling tapering towards the front end to provide for a width of said air suction space increasing from the front end to the rear end thereof, a wall having openings for controlling the flow of cooling air therethrough and being provided between the front cylinders of each row of cylinders, said cowling further comprising an air discharge opening provided in the front portion thereof and arranged on the other side of said longitudinal plane in a region where the outer air pressure is reduced, the rear end of said cowling being closed, whereby the air in

said air suction space flows in a direction opposite to the one of said air pressure space and discharges through said air discharge opening.

4. In an air cooled internal combustion engine having groups of cylinders arranged in line, a device for the distribution of cooling air to the cylinders comprising a cowling surrounding said cylinders and provided with an inlet opening at the front portion thereof positioned laterally on one side with respect to the longitudinal plane passing through the axes of said cylinders, an air pressure space and an air suction space being formed within said cowling, said air pressure space extending behind said inlet opening parallel to and divided by said cylinders from said air suction space extending substantially symmetrical to said air pressure space, the width of said air suction space increasing from the front end to the rear end thereof, said cowling further comprising an air discharge opening, provided in the front portion thereof and arranged on the other side of said longitudinal plane in a region where the outer air pressure is reduced, a wall having controllable openings being provided behind the front cylinders of each row of cylinders for subdividing said air suction space, and air discharge openings provided at the rear end of said cowling.

5. In an air cooled internal combustion engine with cylinders arranged in line, a device for the distribution of cooling air to the cylinders comprising a cowling surrounding said cylinders and provided with an inlet opening at the front portion thereof positioned laterally on one side with respect to the longitudinal plane passing through the axes of said cylinders, an air pressure space and an air suction space being formed within said cowling, said air pressure space extending behind said inlet opening parallel to and divided by said cylinders from said air suction space extending substantially symmetrical to said air pressure space, said cowling being shaped to pro-

vide for a width of said air suction space increasing from the front end to the rear end thereof, said cowling further comprising an air discharge opening provided in the front portion thereof and arranged on the other side of said longitudinal plane in a region where the outer air pressure is reduced, a wall having controllable openings being provided behind the front cylinders of each row of cylinders for subdividing said air suction space, and air discharge openings provided at the rear end of said cowling.

6. In an air cooled internal combustion engine with cylinders arranged in line, a device for the distribution of cooling air to the cylinders comprising a cowling surrounding said cylinders and provided with an inlet opening at the front portion thereof positioned laterally on one side with respect to the longitudinal plane passing through the axes of said cylinders, an air pressure space and an air suction space being formed within said cowling, said air pressure space extending behind said inlet opening parallel to and divided by said cylinders from said air suction space extending substantially symmetrical to said air pressure space, said cowling tapering towards the front end to provide for a width of said air suction space increasing from the front end to the rear end thereof, a wall having controllable openings being provided behind the front cylinders of each row of cylinders for subdividing said air suction space, said cowling further comprising an air discharge opening provided in the front portion thereof and arranged on the other side of said longitudinal plane in a region where the outer air pressure is reduced, the rear end of said cowling being closed, whereby the air in said air suction space flows in a direction opposite to the one of said air pressure space and discharges through said air discharge opening.

WALDEMAR SCHLUPP.
